SELECTIVE FIRE CONVERTER FOR
SEMITAUTOMATIC FIREARMS

Alonzo F. Gaidos, Redwood City, Calif.

Application September 27, 1950, Serial No. 187,035

16 Claims. (Cl. 89—140)

1
This invention relates to a selective fire converter which may be attached to a semi-automatic firearm to provide for semi-automatic fire or full automatic fire at the selection of the marksman.

Heretofore, several selective fire converters have been developed for attachment to the U. S. carbine, caliber .30M1, large quantities of which are now stored. As originally designed, and disclosed in Humeston Patent No. 2,308,283, this weapon is fired semi-automatically, that is, a pull on the trigger fires a single round, reloads a shell in the chamber and cocks the firing mechanism. To fire a second round, the trigger must be released and again pulled. Two of the previously developed selective fire converters are disclosed in my co-pending applications, Serial No. 780,214, filed October 16, 1947, and Serial No. 138,766, filed January 16, 1950. The converters disclosed in these co-pending applications are the only ones which accomplish the desired result without modifying or remachining operating parts of the basic weapon. The present invention is an improvement upon the selective fire converters disclosed in these co-pending patent applications.

A major object of this invention is to provide a selective fire converter having a simplified mechanism which is easier to install and maintain. An important object of the invention is to provide a selective fire converter having component parts which may be more economically manufactured.

In the attainment of these objects, one feature of the invention resides in the construction of a sear tripper which is mounted on the pivot pin for the hammer and is operated by a sliding actuator bar arranged to be reciprocated by the automatically reciprocating slide of the weapon. This sear tripper has a rearwardly extending portion with a sear engaging foot extending downwardly to overlie the sear, and an upwardly extending actuating projection disposed in the path of the actuator bar. Another feature of the invention resides in the arrangement of an actuating member connected by a pivot to the end of the actuator bar and resiliently urged away from the actuating projection on the sear tripper. The actuator bar and actuating member slide in a guideway formed by a casing attached to the receiver by the same bolt which secures the trigger housing to the receiver. Slidable in this same casing is a selector having a cam for shifting the actuating member about its pivot toward the actuating projection on the sear tripper.

Other objects and advantages of the invention

2
will become apparent from the following specification taken in connection with the accompanying drawings wherein:

Figure 1 is a vertical sectional view of a carbine illustrating a preferred embodiment of the invention with some parts broken away for purposes of clearness;

Fig. 2 is a top plan view of the carbine with some parts broken away and others shown in section;

Fig. 3 is a side elevation of the carbine with the selector in its automatic position, some parts being broken away and others shown in section;

Fig. 4 is a fragmentary vertical sectional view of the firing mechanism with some parts broken away and others shown in section, the parts being shown in positions assumed after the trigger is pulled and the hammer has moved to firing position;

Fig. 5 is a view similar to Fig. 1 but showing the slide and bolt retracted to cock the hammer;

Fig. 6 is a view similar to Fig. 4 showing the parts in cocked position with the slide and bolt partially returned to battery position;

Fig. 7 is a fragmentary horizontal sectional view of the firing mechanism shown in Fig. 3;

Fig. 8 is a partial top plan view illustrating the arrangement of the selector;

Fig. 9 is a partial sectional view taken on the line 9—9 of Fig. 7;

Fig. 10 is a fragmentary view similar to Fig. 3, with the selector moved to its semi-automatic position;

Fig. 11 is a perspective view of the sear tripper; and

Fig. 12 is a perspective view of the actuating member on the end of the actuator bar.

A U. S. carbine, caliber .30M1, has a receiver 21 in the forward end of which a barrel 22 is threaded. Locked by a dovetail joint 23 at the rear of the receiver and a transverse bolt 24 at the forward end of the receiver is a trigger housing 25 arranged below the receiver. This housing 25 is formed with a recess 26 in its central portion. A hammer pin 27, extending across the recess 26, pivotally supports a hammer 28 which moves in an arcuate path between a cocked position, as shown in Fig. 1, and a discharge or firing position, as shown in Fig. 4. This hammer 28 has one side formed with a recess 31 (Figs. 2 and 7) extending between its front end 32 and its rear end 33.

Extending across the recess 26 rearwardly of hammer pin 27 is a sear pin 34. A trigger 35 has 55 a pair of ears one of which is illustrated at 36,

extending upwardly through an opening 37 in the bottom of the trigger housing 25 and pivoted on the sear pin 34. Trigger 35 has a rearwardly extending portion 38 above which projects a lip 39. Normally urging the trigger 35 in a counter-clockwise direction as viewed in the drawings is a wire spring 40 secured to the trigger housing. Arranged between the ears on the trigger is a sear 41 formed with an elongated transverse slot 42 through which sear pin 34 is inserted permitting pivotal movement of the sear 41 about the pin 34 and longitudinal shifting movement of the sear with respect to the pin. Extending forwardly from the slot 42, sear 41 has a hammer engaging nose 43 arranged to cooperate with notch 44 in the lower part of hammer 28 to retain the hammer in cocked position. Trigger engaging seat 45 provides a rearward extension on the sear 41 arranged, when the sear is in rearward position as indicated in Fig. 1, to rest on lip 39 on the trigger 35, and, when the sear is in its forward position as indicated in Fig. 6, to rest on the upper surface of the rearwardly extending portion 38 on the trigger 35. Normally urging sear 41 in a forwardly direction is a spring 46 retained in a cylindrical recess 47 formed in portion 38 of the trigger 35 and bearing upon a shoulder 48 extending downwardly from seat 45 on the sear 41.

The construction thus far described is the standard design of the U. S. carbine, caliber .30M1. With the hammer cocked, a pull on trigger 35 acts by engagement of lip 39 with seat 45 on the sear to shift nose 43 out of engagement with notch 44 and permit hammer spring 51 to move the hammer 28 to firing position, as illustrated in Fig. 4. Then, the explosion of the ammunition produces gases under pressure which act on piston 52 in cylinder 53 to move slide 54 rearwardly causing bolt 56 to ride over the top part of hammer 28, as illustrated in Fig. 5. As the slide 54 and bolt 56 return toward battery position, as illustrated in Fig. 6, notch 44 in hammer 28 is engaged by nose 43. If trigger 35 is retained in its pulled position, as illustrated in Fig. 6, seat 45 rests upon the upper surface of the trigger portion 38 and bears against the forward end of lip 39 thereby retaining the hammer 28 in cocked position. To again fire the weapon, trigger 35 must be released permitting seat 45 on sear 41 to move rearwardly above the lip 39. Then, a subsequent pull on the trigger will move the sear in the same fashion as already described.

With a selective fire converter attached to the weapon it may be fired semi-automatically in the same fashion as the basic weapon, or it may be fired automatically in a manner to be described where it will repeat the firing cycle as long as a pull is exerted on the trigger but will stop firing immediately upon release of the trigger.

One component of the selective fire converter is a sear tripper designated generally at 61 and is illustrated in perspective in Fig. 11. This sear tripper 61 has a body portion 62 from which depends an ear 63. A transverse arm 64 extends from the body portion to support another depending ear 65. These ears 63 and 65 are arranged in parallel relation and spaced apart a distance corresponding to the outside widths of the trigger housing at the hammer pin 27. Both ears are provided with aligned holes like the hole 66 in the ear 63 so the sear tripper may be pivotally mounted on the end portions of the hammer pin 27 which project through the walls of the trigger housing. Body 62 of the sear tripper 61

has an inwardly offset portion 67 to which is attached a rearwardly extending arm 68. This arm is relatively thin and generally of arcuate shape lengthwise so it will lie within recess 31 and permit relative movement of the sear tripper and the hammer about the axis of hammer pin 27. Extending downwardly from arm 68 is a sear engaging foot 69 arranged to overlie a raised shoulder or step 71 on the upper surface of nose 43 on sear 41, when the sear is in its forward position, as illustrated in Fig. 6. When the sear is in its rearward position, as illustrated in Fig. 1, foot 69 is disposed forwardly with respect to step 71. Extending upwardly from arm 68 is an actuating projection 72 having at its top a cam surface 73 for a purpose to be described. Actuating projection 72 is normally urged upwardly by a spring 70 connected to the trigger housing and tending to turn the sear tripper in a counter-clockwise direction as viewed in the drawings.

Mounted on the side of the receiver 21 is an elongated casing 74 secured by threaded engagement of depending flange 75 with the same bolt 24 which connects the trigger housing and the receiver. At its rear end, casing 74 has an inwardly projecting hook shaped lug 76 which engages in a recess 77 at the back of the receiver above dovetail joint 23. Casing 74 has a flat exposed side with upper and lower inwardly projecting flanges 80 and 80' forming a guideway along the side of receiver 21. Slidable in this guideway is an actuator bar 78 having its forward part 79 offset outwardly at 81 and extending beside the path along which slide 54 reciprocates. At its front end, forward part 79 of bar 78 is turned inwardly to form an abutment 82 which is engaged by forward edge 83 of the slide 54. Rearward edge 84 of the slide 54 engages front edge 85 of the receiver to arrest rearward movement of the slide. This rearward edge 84 of the slide 54 has an undercut edge 86 which engages an abutment 87 formed on the inner face of actuator bar 78 just rearwardly of offset 81.

When the slide 54 is in its most forward position, as illustrated in Fig. 3, the distance (indicated by dotted line A) from rearward edge 84 of the slide to forward edge 85 of the receiver is slightly greater than the distance (indicated by dotted line B) from undercut edge 86 on the slide 54 to abutment 87. Upon reciprocation of the slide 54 in a rearward direction, undercut edge 86 engages abutment 84 to move actuator bar 78 a short distance rearwardly from its position, as shown in Fig. 3, to the position shown in Fig. 5, where rearward edge 84 of the slide 54 engages forward edge 85 of the receiver 21. Then, return of slide 54 to its forward position will reverse the sliding movement of the actuator bar just as the slide returns the bolt 56 to its battery position, as illustrated in Fig. 7. This limited reciprocating movement of the actuator bar produces a pivotal movement of the sear tripper by means of the actuator mechanism now to be described.

As illustrated in Fig. 10, rear end of actuator bar 78 is provided with an inwardly offset end portion 91 to which is connected by pivot pin 92 an actuating member 94. Actuating member 94 has a horizontal flange 95 extending inwardly and rearwardly. At the back of the flange 95 is a cam 99 arranged to ride over cam surface 73 on actuating projection 72 of the sear tripper when actuator bar 78 is reciprocated by the slide 54. Wire spring 101, which is wound

on pivot 92 is arranged to act between bar 78 and member 94 to resiliently urge actuating member 94 with its cam 99 about the pivot 92 away from actuating projection 72 on the sear tripper 61. Forward movement of the actuator bar 78 is limited by a lug 97 extending inwardly from the bar 78 and arranged to engage wall 98 in the receiver.

Slidable at the rear end of casing 74 is a selector 102 having a body portion 103 slidable in opening 104 formed in the upper flange 80 of the casing. Forwardly extending fingers 105 and 106 are separated a distance equal to the thickness of flange 80 so they slide along the upper and lower surfaces of the flange. On rearwardly extending portion 107 is an operating flange 108 having a knurled surface accessible to the thumb of the marksman so the selector may be shifted forward or backward. A spring 109 extends rearwardly from body portion 102 and has links arranged to enter openings in the flange 80 to serve as a detent for the selector. With the selector 102 in forward position so detent 109 is engaged in opening 104, as indicated in Fig. 3, inclined cam surface 110 on the bottom of flange 106 engages a corresponding cam surface 111 on actuating member 94 to depress the actuating member so actuating projection 99 will engage cam surface 73 on the sear tripper. When selector 102 is shifted to its rearward semi-automatic position, detent 109 engages opening 112, as indicated in Fig. 10. In this position inclined cam surface 110 on the selector is disengaged from cam surface 111 on the actuating member 94 thereby permitting spring 101 to shift cam 99 upwardly so it will not operate the sear tripper.

With selector 102 in its forward or automatic position, as illustrated in Fig. 3, a pull on the trigger 35 removes sear nose 41 from engagement with the hammer notch 44 so the gun will fire the first round. Exhaust gases act upon piston 52 which moves slide 54 rearwardly so bolt 56 cocks hammer 28, as illustrated in Fig. 5. As the slide approaches its rearmost position, undercut edge 86 engages rear abutment 87 on the actuator bar to reciprocate the bar and actuating member 94 rearwardly. Further rearward movement of the slide 54, until rearward edge 84 engages forward edge 85 of the receiver, reciprocates the actuator bar 78 rearwardly and thereby moves cam 99 rearwardly with respect to cam surface 73 on actuating projection 72. This rearmost position of the cam 99 is illustrated in Figs. 5 and 6, and in dotted lines in Fig. 1.

When the slide and bolt move forwardly toward battery position, hammer 28 is retained in cocked position by engagement of nose 43 on the sear with notch 44 on the hammer, as illustrated in Fig. 6. At this point, the sear is retained in its forward position by engagement of sear seat 38 with lip 39 on the trigger. Thus, the sear engaging foot 69 on the sear tripper overlies raised step 71 on the sear.

As the slide and bolt return to battery position, forward edge 83 on the slide engages abutment 82 on the forward end of the actuator bar to move the actuator bar with actuating member 94 and cam 99 forwardly. With this forward movement of the actuating member, cam 99 depresses cam surface 73 on actuating projection 72 against the force of spring 70, thereby pivoting the sear tripper 61 about the hammer pin 27 and depressing foot 69 onto raised step 71 on the sear and depressing the sear to release the ham-

mer 28 to again fire the weapon and repeat the same cycle. This automatic cycle continues to repeat until the trigger 35 is released. Then, as the slide moves, actuator bar 78 forwardly to depress the sear tripper, foot 69 will be depressed in front of raised step 71 because, upon release of the trigger the sear will move to its rearward position, as illustrated in Fig. 1.

When semi-automatic operation of the weapon is desired, the operator moves serrated flange 100 rearwardly to shift selector 102 to its rearward or semi-automatic position with detent 109 engaged in opening 112. This movement of the selector moves cam surface 110 out of engagement with cam surface 111 so the actuating member 94 pivots away from the sear tripper so cam 99 is withdrawn from a position where it will engage cam surface 73 on the sear tripper. A pull on the trigger will cause the gun to fire and the slide and bolt to cock the hammer. Reciprocation of the slide produces reciprocation of the actuating bar 78, but reciprocation of the actuating member 94 and the cam 99 is ineffective because the cam does not engage the actuating projection on the sear tripper. Hence, the weapon will fire a single shot and then remain in cocked position until the trigger is released and again pulled.

It will be apparent that the component parts 30 of the selective fire converter disclosed herein may be very easily manufactured. The actuator bar 78 and the actuating member 94 may be stamped from metal stock. A simple rivet provides the pivot 95 connecting these two parts. 35 Likewise, sear tripper 61 and selector 102 may be made on stamping machines. To incorporate this selective fire converter in a standard carbine, it is only necessary to replace the sear in the carbine with a sear having a raised step 71 on its hammer engaging nose. The hammer pin is removed and an elongated hammer pin 27 is inserted with the sear tripper in place. Actuator bar 78 and selector 102 are assembled in casing 74 and secured by transverse screw 24 which replaces the pin in the standard carbine. Thus, the component parts are not only economically manufactured but may be quickly assembled by a soldier in the field and very easily maintained.

What is claimed is:

1. An automatic firearm comprising a receiver, a trigger housing, an automatically reciprocating slide on said receiver; a hammer pin extending through said housing; a hammer pivoted on said pin, a trigger pivotally mounted in said housing; a sear having an elongated slot; a pin extending through said slot and mounted in said housing, a forwardly extending hammer engaging nose on said sear arranged to cooperate with a notch in said hammer and retain said hammer in cocked position; a raised step on said nose, a rearwardly extending trigger engaging seat on said sear overlying said trigger; a sear tripper pivoted on said hammer pin, a sear engaging foot on said tripper overlying said step, an upwardly extending actuating projection on said sear tripper, an actuator bar reciprocable by said slide and an actuating member on said bar arranged to engage said projection and move said sear tripper in a manner causing said nose to depress said sear.

2. An automatic firearm comprising a receiver, a trigger housing, an automatically reciprocating slide on said receiver; a hammer pin extending through said housing; a hammer pivoted on said pin, a trigger pivotally mounted in

said housing, a sear having an elongated slot, a pin extending through said slot and mounted in said housing, a forwardly extending hammer engaging nose on said sear arranged to cooperate with a notch in said hammer and retain said hammer in cocked position, a raised step on said nose, a rearwardly extending trigger engaging seat on said sear overlying said trigger, a sear tripper pivoted on said hammer pin, a sear engaging foot on said tripper overlying said step, an upwardly extending actuating projection on said sear tripper, an actuator bar reciprocable by said slide, an actuating member on said bar arranged to engage said projection and move said sear tripper in a manner causing said nose to depress said sear, and a movable selector connected with said actuating member for shifting said member relative to said actuating projection.

3. An automatic firearm comprising a receiver, a trigger housing, an automatically reciprocating slide on said receiver, a hammer pin extending through said housing, a hammer pivoted on said pin, a trigger pivotally mounted in said housing, a sear having an elongated slot, a pin extending through said slot and mounted in said housing, a forwardly extending hammer engaging nose on said sear arranged to cooperate with a notch in said hammer and retain said hammer in cocked position, a raised step on said nose, a rearwardly extending trigger engaging seat on said sear overlying said trigger, a sear tripper pivoted on said hammer pin, a sear engaging foot on said tripper overlying said step, an upwardly extending actuating projection on said sear tripper, an actuator bar reciprocable by said slide, and an actuating member pivotally connected to the end of said bar to engage said projection and move said sear tripper in a manner causing said nose to depress said sear.

4. An automatic firearm comprising a receiver, a trigger housing, an automatically reciprocating slide on said receiver, a hammer pin extending through said housing, a hammer pivoted on said pin, a trigger pivotally mounted in said housing, a sear having an elongated slot, a pin extending through said slot and mounted in said housing, a forwardly extending hammer engaging nose on said sear arranged to cooperate with a notch in said hammer and retain said hammer in cocked position, a raised step on said nose, a rearwardly extending trigger engaging seat on said sear overlying said trigger, a sear tripper pivoted on said hammer pin, a sear engaging foot on said tripper overlying said step, an upwardly extending actuating projection on said sear tripper, an actuator bar reciprocable by said slide, an actuating member pivotally connected to the end of said bar, and a movable selector for shifting said actuating member relative to said actuating projection.

5. An automatic firearm comprising a receiver, a trigger housing, a bolt securing said housing to said receiver, an automatically reciprocating slide on said receiver, a hammer pivotally mounted in said housing, a trigger pivotally mounted in said housing, a sear having an elongated slot, a pin extending through said slot and mounted in said housing, a forwardly extending hammer engaging nose on said sear arranged to cooperate with a notch in said hammer, a raised step on said nose, a rearwardly extending trigger engaging seat on said sear overlying said trigger, a sear tripper pivotally mounted on the pin for said hammer, a sear engaging foot on said tripper overlying said step, an upwardly extending actuating projection on said sear tripper, an actuator bar reciprocable by said slide, and an actuating member on said bar arranged to engage said actuating projection upon reciprocation of said bar.

6. An automatic firearm comprising a receiver, a trigger housing, a bolt securing said housing to said receiver, an automatically reciprocating slide on said receiver, a hammer pivotally mounted in said housing, a trigger pivotally mounted in said housing, a sear having an elongated slot, a pin extending through said slot and mounted in said housing, a forwardly extending hammer engaging nose on said sear arranged to cooperate with a notch in said hammer, a raised step on said nose, a rearwardly extending trigger engaging seat on said sear overlying said trigger, a sear tripper pivotally mounted on the pin for said hammer, a sear engaging foot on said tripper overlying said step, an upwardly extending actuating projection on said sear tripper, a casing extending along the side of said receiver and secured thereto by said bolt, an actuator bar slidably in said casing and reciprocable by said slide, and an actuating member pivotally connected to said bar and arranged to engage said projection and move said sear tripper to depress said sear upon reciprocation of said bar.

6. An automatic firearm comprising a receiver, a trigger housing, a bolt securing said housing to said receiver, an automatically reciprocating slide on said receiver, a hammer pivotally mounted in said housing, a trigger pivotally mounted in said housing, a sear having an elongated slot, a pin extending through said slot and mounted in said housing, a forwardly extending hammer engaging nose on said sear arranged to cooperate with a notch in said hammer, a raised step on said nose, a rearwardly extending trigger engaging seat on said sear overlying said trigger, a sear tripper pivotally mounted on the pin for said hammer, a sear engaging foot on said tripper overlying said step, an upwardly extending actuating projection on said sear tripper, a casing extending along the side of said receiver and secured thereto by said bolt, an actuator bar in said casing reciprocable by said slide, an actuating member pivotally connected to said bar, and a selector member mounted on said casing for shifting said actuating member relative to said actuating projection.

7. An automatic firearm comprising a receiver, a trigger housing, a bolt securing said housing to said receiver, an automatically reciprocating slide on said receiver, a hammer pivotally mounted in said housing, a trigger pivotally mounted in said housing, a sear having an elongated slot, a pin extending through said slot and mounted in said housing, a forwardly extending hammer engaging nose on said sear arranged to cooperate with a notch in said hammer, a raised step on said nose, a rearwardly extending trigger engaging seat on said sear overlying said trigger, a sear tripper pivotally mounted on the pin for said hammer, a sear engaging foot on said tripper overlying said step, an upwardly extending actuating projection on said sear tripper, a casing extending along the side of said receiver and secured thereto by said bolt, an actuator bar slidably in said casing, spaced abutments on the forward end of said bar engageable by said slide to reciprocate said bar, and an actuating member on said bar arranged to engage said actuating projection.

8. In an automatic firearm having a hammer pivotally mounted on a hammer pin, a sear for engaging a notch in said hammer, and an automatically reciprocating slide for cocking said hammer, a selective fire converter comprising a sear tripper pivotally mounted on said hammer pin, a sear depressing foot on said sear tripper overlying said sear, an actuating projection on said sear tripper, an actuator bar reciprocated by said slide, and an actuating member on said bar arranged to engage said actuating projection upon reciprocation of said bar.

9. In an automatic firearm having a hammer pivotally mounted on a hammer pin, a sear for engaging a notch in said hammer, and an automatically reciprocating slide for cocking said hammer, a selective fire converter comprising a sear tripper pivotally mounted on said hammer pin, a sear depressing foot on said sear tripper overlying said sear, an actuating projection on

said sear tripper, an actuator bar reciprocated by said slide, an actuating member pivoted on said bar, and a movable selector connected to said member for shifting said member relative to said projection.

10. In an automatic firearm having a hammer pivotally mounted on a hammer pin, a sear for engaging a notch in said hammer, and an automatically reciprocating slide for cocking said hammer, a selective fire converter comprising a sear tripper pivotally mounted on said hammer pin, a sear depressing foot on said sear tripper overlying said sear, an actuating projection on said sear tripper, an actuator bar reciprocated by said slide, an actuating member pivotally connected to the end of said bar, spring means resiliently urging said member away from a position to engage said projection upon reciprocation of said bar, and a movable selector connected to said member for shifting said member against said spring means to a position to engage said projection.

11. In an automatic firearm having a hammer pivotally mounted on a hammer pin, a sear for engaging a notch in said hammer and an automatically reciprocating slide for cocking said hammer, a selective fire converter comprising a sear tripper pivotally mounted on said hammer pin, a rearwardly projecting arm on said sear tripper, a sear depressing foot extending downwardly from said arm to overlie said sear, an actuating projection extending upwardly from said arm, an actuator bar reciprocated by said slide, and an actuating member on said bar arranged to engage said projection and move said sear tripper to depress said sear.

12. In an automatic firearm having a hammer pivotally mounted on a hammer pin, a sear having an elongated slot permitting longitudinal shifting of said sear on a pin through said slot, a raised step on the hammer engaging nose of said sear, and an automatically reciprocated slide for cocking said hammer, a selective fire converter comprising a sear tripper pivotally mounted on said hammer pin, a rearwardly projecting arm on said sear tripper, a sear depressing foot extending downwardly from said arm and overlying said step only when said sear is shifted forwardly, an actuating projection extending upwardly from said arm, an actuator bar reciprocated by said slide, and an actuating member on said bar arranged to engage said projection upon reciprocation of said bar.

13. In a selective fire converter for an automatic fire arm having a trigger housing, a hammer pivotally mounted therein, a sear for engaging said hammer, an automatically reciprocated slide for cocking said hammer, and an actuator bar reciprocated by said slide; a sear tripper comprising a body, a first ear depending

from said body, a transversely extending portion on said body, a second ear depending from said portion parallel to said first ear and spaced therefrom a distance corresponding to the outside

5 width of the trigger housing, said ears being formed with alined holes to mount said sear tripper on the pivot pin for said hammer, a rearwardly extending arm on said body, a sear engaging foot extending downwardly from said arm, and an actuating projection extending upwardly from said arm to be engaged by said actuator bar.

14. In a selective fire converter for an automatic fire arm having a trigger housing, a hammer pivotally mounted therein, the hammer being

15 formed with a longitudinally extending recess in one side, a sear for engaging said hammer, an automatically reciprocating slide for cocking said hammer, and an actuator bar reciprocated by said slide; a sear tripper comprising a body, a

20 first ear depending from said body, a second ear depending from a transversely extending portion of said body parallel to and spaced from said first ear a distance corresponding to the outside width of the trigger housing, said ears being formed

25 with alined holes to mount said sear tripper on the pivot pin for said hammer, an arcuately shaped rearwardly extending arm inwardly offset from said first ear to lie within the recess in said hammer and permit relative movement of said sear tripper and said hammer on the pivot pin for said hammer, a sear engaging nose depending from said arm, and an actuating projection extending upwardly from said arm into the path of said actuator bar.

30 15. In a selective fire converter for an automatic firearm having a pivotally mounted hammer, a sear for engaging said hammer, an automatically reciprocating slide for cocking said hammer and a pivotally mounted sear tripper for depressing said sear; actuator mechanism comprising a longitudinally extending casing, an actuator bar slidably mounted in said casing along the path of said slide, spaced abutments on said actuator bar engageable by said slide to recip-

40 rocate said bar, an actuating member pivoted to the rear end of said actuator bar, spring means resiliently urging said member away from said sear tripper, and a selector slidable on said casing to move said member toward said sear tripper against the force of said spring.

45 16. In a selective fire converter for automatic firearms, actuator mechanism as defined in claim 15 wherein said selector has a cam engageable with said actuating member to move said member about said pivot against the action of said spring means.
